Attorney,

UNITED STATES PATENT OFFICE.

JONATHAN L. JONES, OF ST. LOUIS, MISSOURI.

TRUSS-BRIDGE.

Specification of Letters Patent No. 30,577, dated November 6, 1860.

To all whom it may concern:

Be it known that I, JONATHAN L. JONES, of St. Louis, State of Missouri, have invented a new and useful Improvement in 5 Metallic-Truss Bridges; and I do hereby declare that the following is a full, clear, and exact description of the same, reference being had to the accompanying drawings, forming a part of this specification, in 10 which—

Figure 1, represents a longitudinal vertical section; Fig. 2, a horizontal cross section, and Fig. 3, a vertical cross section of my improved metallic truss bridge; Fig. 4, 15 a detached view; Figs. 5 and 6 are sectional views of a diagonal brace. Fig. 7, is a perspective view of a portion of the lower chord &c.

Similar characters of reference in each of 20 the several figures indicate corresponding parts.

The trusses of this bridge consist of a system of chords and stringers, braces and screw rods, all arranged in such manner that the 25 component parts of each truss can accommodate themselves to such variations in the camber or vertical curvature of the bridge as may be produced by changes of temperature, heavy weights, and similar causes.

30 The nature of my invention consists, first, in the flexible scarfed splice in the lower chord, when said splice is formed of broad flat plates with lateral curved offsets or lugs formed on their ends, said offsets pulling 35 against one another and allowing a free independent movement of each plate in the path of a vertical circle, as hereinafter described.

It consists, second, in combining the convex 40 surface of the blocks above and hereinafter described with corresponding concave flanges at the ends of the tubular braces for the purpose of insuring a perfect bearing of these parts during any change in the camber or 45 vertical curvature of the bridge that may be produced in adjusting the same, or by the expansion or contraction of the chords, plates or tubes.

It consists, third, in the formation of metallic 50 recessed blocks in combination with the above described joints in the lower chord, which block clamps and secures the joints of the plates or chords from the under edge, by the action of the vertical screw bolts f , 55 causing it to come in contact with the under-

portion of the convex block—but does not prevent the free motion of the joints.

It consists, fourth, in combining the bottom stringers of the bridge with grooved shoes for the three fold purpose of sustaining the 60 floor beams, preventing any possibility of the collapsing or buckling of the wrought-iron chords or plates and to assist in forming the lateral fastenings between two trusses at the bottom.

It consists, fifth, in constructing the diagonal tubular brace with a septum or longitudinal partition and transverse tubes as hereinafter described.

It consists, sixth, in the peculiar construction 70 of the metallic abutment shoe upon which the truss rests at its extremities.

To enable others skilled in the art to make and use my invention, I will proceed to describe its construction and operation.

The system of bottom chords consists of independent sections or plates of wrought iron $a, a, a, b, b, b, c, c, c$, Fig. 2, which are provided with a shoulder forming a joint at each end. The inner edge of the shoulder 80 of one plate is intended to bear against the inner edge of the shoulder of the next plate as shown in Fig. 2 when for instance the shoulders $b''' b'''$ of the plates $b' b'$ are represented as locked into and resting against 85 the shoulders $c''' c'''$ of the plates $c' c'$. The edges y, z , of the shoulders in contact with each other are rounded as seen in Fig. 4, so that a perfect bearing will be insured although the angle which the two plates 90 form with each other may change. The shoulder ends of the plates thus hooked or locked into each other are sunk into corresponding recesses in the tops and bottoms e 95 of the blocks, thereby clamping and preventing the splicer or joints from becoming unjointed by lateral or other motion, and at the same time retaining the entire strength of the iron chords by avoiding the use of bolts or rivets passing through the chords. 100 These recesses in the blocks are made flaring from the center of the blocks toward the outside as shown at $x' x'$ so that the plates can change the angle they form with each other and thus accommodate themselves to the 105 varying camber of the bridge without being strained in the blocks $d e$. The stringers a at each end of the bridge pass through slots in a shoe (j) and are provided with shoulders a''' at their outer ends resting against 110

the outer face j''' of the shoe. The shoe has an extension j'' j''' in the rear as seen in Figs. 1 and 2.

The wrought iron tension plates or top 5 stringers g , h , i are locked into each other by means of the same splice or joint employed to connect the chords below, as before described and are designed to prevent any derangement of the plates in adjusting 10 the truss when raising the bridge.

In addition to the top stringers above described, cast iron tubular braces z are placed longitudinally between each two of the blocks d' , e' , to the convex surface of which 15 they are fitted by the corresponding concave surfaces of the ends of the above described tubular braces z . These braces are designed to act as plates and to resist the compressive action of the upper portion of 20 the bridge while sustaining its own weight or a heavy load previous to which in raising the bridge they are held to their places by the action of the screws of the top stringers and the diagonal screw bolts at the end 25 of the bridge.

The blocks (d e) clamping the bottom stringers and the blocks (d e) clamping the center tension plates of the top, are fastened together by vertical screw rods (f). The 30 top blocks (d e) of the upper stringers at each end of the bridge are held to the shoe (j) or lower end block by similar screw rods (f). These upper blocks at the intersecting point of each section of the truss 35 answer a three-fold purpose—first, that of a bearing for the diagonal braces; second, as a clamp for the splicer of the tension plates of the upper stringers and, third, to assist in forming a part of the cylindrical 40 knuckle joints of the upper plates or tubes as before mentioned.

To make the truss a self sustaining structure of the necessary rigidity a series of diagonal braces (o) are arranged in the 45 usual manner, as follows: A tubular counter brace extends from the first block d e of the top stringers to the second block of the chords; another brace parallel to the first extends from the second block of the top 50 stringer to the third block of the bottom chord, a similar counter brace being inserted into each section successively.

At the extreme end of the truss a pair 55 of main braces (o' , o'') extend from the convex (s), at the outer end of the shoe (j) to the first block on the extreme end of the top stringers or tubular plates. Then a pair of main braces diagonally crossing outside of the before described counter braces is extended from the interior convex end of the 60 shoe (j) to the second block of the tubular plates or stringers. A parallel pair of braces also extends from the second block of the chord to the third block of the top and so 65 on successively.

The surfaces of the shoe as seen at (k) and of the blocks against which the ends of the braces (o) bear are convex and the ends of the braces are provided with concave flanges (t) of a corresponding curve. Thus it is 70 seen a perfect bearing of these parts will be insured during such slight changes in the relative portions of the component parts of the bridge as will occasionally occur for reasons before named. The lower ends of 75 the braces (o) are also provided with similar concave flanges (t) resting against the convex portions of the shoe. The two end braces (o) are connected by a transverse tube (p) and bolt (r) passing through the braces 80 and transverse tube. The braces (o) are at the point of intersection constructed with transverse tubes (p) the ends of which may be enlarged and extended from the outer circumference of the brace so as to rest 85 against each other, or they may terminate at the outer circumference of the brace as shown in Figs. 5 and 6. Bolts (r) pass through these transverse tubes and hold the 90 braces together in a transverse direction, at 95 the same time allowing them to play around the bolts as their center. In order that the braces may have sufficient strength at these points of intersection and still be light, they are made hollow and strengthened by a septum or longitudinal partition (Fig. 2) 100 which comes within the bore of the brace and ties the upper and under portions of its inner circumference together in the manner represented in Figs. 5 and 6 of the drawing. 105 By this mode of construction it is obvious that great strength is imparted to the braces and they are thereby enabled to resist the cross sectional strain which is produced to a considerable extent by the longitudinal 110 thrust or concussion that occurs during the passage of a train of cars.

The cylindrical blocks of the top stringers are provided with brackets (l) through 110 which diagonal holes (m , n) are made for the insertion of diagonal screw rods laterally connecting the tops of two trusses. These trusses are kept apart laterally by 115 tubular braces crossing the bridge at right angles and resting against the beveled surfaces of the bracket (l). Shoes (w) are arranged across the bottom chords, provided with grooves into which the chords fit. The 120 chords are thus kept at their proper distances apart and any possibility of their collapsing or buckling is effectually prevented.

The floor beams (v) are placed on and bolted to the shoe by means of bolts (x) and form the lateral fastening at the bottom of the trusses.

What I claim as my invention and desire to secure by Letters Patent is—

1. The flexible curved splice in the lower chord when said splice is formed of broad flat plates c , c' , b' , b'' , with lateral curved 125

20

offsets or lugs c''', b''' , formed on their ends; said offsets pulling against one another and allowing a free independent movement of each plate in the path of a vertical circle, substantially as set forth.

2. The combination of the convex or arched surface of blocks d, k, s, e, d', e', x' , with similarly convex or concave flanges t , at the ends of the tubular braces o , and z , substantially as and for the purposes set forth.

3. The metallic clamps or recessed blocks d, e, d', e' , for retaining and holding together the tension joints of the upper and lower chords or stringers in the manner and for the purposes set forth.

4. The grooved shoe w , which connects

and ties the lower chords and floor beams together, substantially as and for the purposes set forth.

5. The septum or longitudinal portion q , and transverse tubes p , combined within the bore of the tubular brace o , in the manner and for the purposes set forth.

6. The shoe j , as constructed and combined with the lower ends of the tubular diagonal brace and the extreme end a, a , of the lower chords, substantially as and for the purposes set forth.

JONATHAN L. JONES.
